MEASURED SERVICE TELEPHONE SYSTEM

Kurt Wollack, Berlin, Germany, assignor to
 Siemens & Halske Aktiengesellschaft, Wernerwerk Siemensstadt, near Berlin, Germany

Application September 26, 1935, Serial No. 42,239
 In Germany October 2, 1934

9 Claims. (Cl. 179—7.1)

The present invention relates to a circuit arrangement for metering variously rated calls in remote communication systems, more particularly in telephone systems.

5 In such systems it is a well known practice to effect the metering operation after the completion of a call. This method has several advantages. For example, it is possible in particular cases, such as the breaking down of a low rated call in favour of one more expensive, to suppress the metering. Furthermore, if only the speaking leads are available for the transmission of the metering impulses, it avoids the necessity for providing special balancing devices dependent 15 upon the device receiving the metering impulses, which if the metering impulses are to be transmitted during the call have to be attached permanently to one of the speaking leads.

If, however, a highly rated call is set up for 20 which an impulse train consisting of a large number of metering impulses has to be transmitted after the completion of the call, it may not be practical to transmit the metering impulses only at the close of the call since, especially in times of heavy traffic, the withdrawal or release of the connecting devices and switches and use of the line until the end of the metering may be very disadvantageous to the operation of the system.

The object of the invention is to enable the 25 metering of highly rated calls to take place during the existence of the call while obviating the necessity for providing special balancing devices in the line, and this is accomplished by providing two switching paths for the metering impulses, in 30 one of which switching means occur which only connect up the device for receiving the metering impulse at the moment for effecting the metering, while the other path contains a device (glow lamp) which does not disturb the symmetry of 35 the speaking lines, over which device a metering impulse receiving device is permanently connected to the metering lead (speaking lead).

The present invention may be applied with considerable advantage to large telephone systems 40 where it is possible to meter local calls without using the current source of high potential necessary for the striking of the glow lamp, and it is thus unnecessary to provide these current sources in all the exchanges of the system but only 45 in one (main exchange) or a few of the exchanges of the network, over which highly rated or toll calls are set up.

Embodiments of the invention are shown in Fig. 1 and Fig. 2 of the drawing. A subscriber 50 *Tn* can reach a desired subscriber by way of a pre-

selector *VW*, a first group selector *IGW* and other connecting devices of which those subsequent to the first group selector are only partially represented.

In Fig. 2 another first group selector is shown 5 as a second embodiment. The preselector and the devices subsequent to the group selector are identical with those of Fig. 1 and are therefore omitted.

When subscriber *Tn*, Fig. 1, removes his receiver 10 in order to set up a call, the following circuit is set up for relay *R*: earth, winding of relay *R*, contact *2t*, subscriber's loop, contact *3t*, resistance *W1*, battery, earth. At contact *7r* relay *R* completes the operating circuit for rotary magnet *D* 15 of preselector *VW*: earth, battery, contacts *7r*, *6t*, rotary magnet *D*, relay interrupter *RU*, earth. Under the influence of the relay interrupter the wipers *a*, *b*, *c*, *d*, of the preselector are stepped 20 round until they find a free first group selector *IGW*. The following testing circuit is then set up over wiper *c*: earth, battery, contact *8r*, windings *II* and *I* of relay *T*, wiper *c* of preselector *VW*, resistance *W2*, contact *20b*, off normal contact *21k* (opened after the first vertical step of the 25 group selector), windings *II* of relays *A* and *B*, earth. In this circuit relay *T* of the preselector energizes (the meter *Z* in parallel with winding *I* of relay *T* does not energize), as do also relays *A* and *B* in the first group selector. The opening 30 of contact *6t* breaks the advancing circuit for rotary magnet *D* of the preselector so that this switch is brought to rest. By the closing of contact *5t* the high resistance winding *II* of relay *T* is short-circuited, thus preventing a double 35 seizure of the free group selector which has been reached. By the opening of contacts *2t* and *3t* the circuit for the line relay *R* is broken and the speaking leads are switched through to the subsequent group selector *IGW* by the closing of contacts *1t* and *4t*. The feeding of talking current 40 to the calling subscriber *Tn* then takes place over windings *I* of relays *A* and *B* in the following circuit: earth, contact *9a*, winding *I* of relay *B*, wiper *b* of preselector *VW*, contact *4t*, subscriber's 45 loop, contact *1t*, wiper *a* of the preselector, winding *I* of relay *A*, battery, earth. After the release of relay *R* and the opening of contacts *7r* and *8r*, the high resistance winding *II* of relay *T* is disconnected, and the guarding circuit follows the 50 following path: earth, battery, restoring wiper *d* of preselector *VW* in the working position, contact *5t*, winding *I* of relay *T* (and in parallel the winding of the meter *Z*, although the latter cannot 55

energize in this circuit), and over wiper *c* to the group selector IGW.

In the group selector relays A and B have been energized. By the opening of contact 20b relay 5 C has its short circuit removed so that it is brought into the circuit set out above, and energizes. By the closing of contact 22c a locking circuit is established for relay C over resistance Wi3.

10 The setting of the group selector IGW takes place in the well known manner. Accordingly the switching elements necessary for setting the selector, such as the vertical and rotary magnets, and the controlling means appertaining thereto, 15 etc., are not shown in Fig. 1.

It will now be assumed that subscriber Tn sets up a local call within the same exchange, or a call for which the meter Z of the calling station is advanced only once.

20 When the wipers of the group selector IGW have been raised to a particular level by the first impulse train and have automatically sought out a subsequent free connecting device for example a final selector LW, the following testing circuit 25 is set up: earth, contact 26c, winding II of relay P, winding I of relay P whose short-circuit is removed at contact 25c, wiper *c* of the first group selector, winding of relay C1 in the final selector, battery, earth. In this circuit relay P of the 30 first group selector and relay C1 of the final selector both energize. By the closing of contact 24p the high resistance winding II of relay P is disconnected and thus the subsequent connecting device that has been taken into use is protected 35 against further seizure. At contacts 16p and 17p the speaking leads are switched through to the subsequent connecting device. The subscriber now dials the second and third digits of the desired number and thereby sets the final selector 40 LW in the well known way on the called line. This is represented in the drawing only in so far as it is necessary for an understanding of the invention.

When the desired subscriber replies the final selector LW moves into speaking position by the 45 controlling switch being brought to position 8, in which contact S8 is closed. The winding of relay Q which is connected to earth is thereby connected to the upper speaking lead.

50 When, at the end of the conversation, subscriber Tn replaces his receiver, relays A and B in the first group selector release. By the closing of contact 20b the winding of relay C is short-circuited so that this relay deenergizes shortly afterwards. By the opening of contact 15c the lower speaking lead in the first group selector is disconnected, while the closing of contact 14c connects the metering relay Z1 to the lower speaking lead. The following circuit is set up by the closing of contact 29c: earth, battery, winding III of relay P, contacts 29c, 16p, wiper *a* of the group selector, control switch contact S8, winding of relay Q, earth. Relay Q in the final selector energizes in this circuit, and relay P in the group selector holds up although its winding I has been short circuited by contact 25c. A premature release of the group selector is thus prevented. By the closing of contact 27q in the final selector the following circuit is set up: earth, battery, 65 resistance Wi5, contact 27q, wiper *b* of the first group selector, contacts 17p, 14c, winding of local call relay Z1, earth. In this circuit relay Z1 energizes and operates its contact 18z1. Resistances Wi2 and Wi3 are thereby short circuited (contact 70 22c does not open before contact 18z1 has closed)

and the current over the testing lead of the pre-selector is thus increased and causes the advancement of the meter Z of the calling subscriber Tn. The local call metering relay Z1 closes its contact 28z1 thus short circuiting winding III of relay P 5 which thereupon releases and initiates the release in the known way.

If the called subscriber replaces his receiver before the calling subscriber the controlling switch of the final selector is moved to position 9. 10 In this case no energizing of relay Q in the final selector takes place. Instead the control switch contact S9 is closed and this immediately connects battery for metering to the lower speaking lead. After the replacement of the receiver at 15 the calling station and the release of relay C the metering relay Z1 is energized and brings about 20 the metering and the release as described above.

The case will now be considered in which the calling subscriber sets up a highly rated or toll 25 call. The setting of the preselector takes place in the manner already described. The group selector IGW is now raised to a level to which a connecting toll line VL leading to another exchange, for example the main exchange, is connected. The testing circuit then passes over resistance Wi4 instead of relay C1. Only those individual parts of the connecting device reached over the connecting line which are necessary for the explanation of the invention, are shown. 30 These comprise a contact 48x which is closed during the transmission of a metering impulse train, and a contact 47zf which connects the lower speaking lead over a resistance Wi6 to a powerful battery for striking the glow lamp. This contact 35 47zf is under the influence of a meter advancing device which on the commencement of the conversation and then after a time interval of definite duration closes and opens the contact 47zf a different number of times according to the 40 selected call direction. In this way metering impulse trains, whose length is defined by the cost of the call, are transmitted by the meter advancing device (not shown) to the lower speaking lead at definite time intervals. On the transmission of a metering impulse train by the meter 45 advancing device the toll call relay Z2 is energized intermittently in the following circuit: earth, striking battery for the glow lamp, resistance Wi6, contact 47zf, lower speaking lead, wiper b of the first group selector, contacts 17p, 15c, 50 glow lamp G1, metering relay Z2, earth. Metering relay Z2 thus closes its contact 19z2 several times thereby increasing the current over the testing lead of the preselector and thus advancing the meter of the calling subscriber corresponding 55 to the influencing of the metering relay Z2.

In addition the toll call metering relay Z2 closes its contact 23z2 intermittently thus establishing the following circuit for the delayed release relay E which keeps its contacts in the working position during the brief current interruptions: earth, contact 23z2, winding of relay E, battery, earth. Relay E opens its contacts 10e and 13e thus 60 breaking the speaking leads, and closes contacts 11e and 12e whereby a buzzer signal is connected up which indicates to the calling subscriber that the metering is occurring at this moment. During this time, which, of course, is very brief, perhaps one-half to one second conversation cannot 65 be heard. When the particular number of impulses have been transmitted contact 23z2 is opened for a longer time and relay E deenergizes. The speaking leads are switched through again 70 and conversation can commence or can be dis- 75

continued. During the transmission of the buzzer signal the subscriber can, by quickly hanging up his receiver, interrupt the call and thereby prevent a further operation of his meter. For indicating the metering operation, switching means can be provided in the meter advancing device which sends out a notification signal over the speaking lines some time before the transmission of the metering impulses for example ten seconds previously. The calling subscriber can then bring his conversation to an end quickly within the ten second period still remaining.

If the subscriber T_n replaces the receiver during the transmission of a metering impulse train either by chance or because he hears the signal indicating the occurrence of the metering operation, the whole of the impulse train is nevertheless transmitted as before. Thus if relay C deenergizes during the transmission of the metering impulses while only a part of the metering impulse train has been transmitted to metering relay Z_2 over the glow lamp, the remaining impulses are taken up by the metering relay Z_1 , this occurring in the following circuit: earth, winding of metering relay Z_1 , contacts $14c$, $17p$, wiper b of the first group selector, connecting line VL , contact $47zf$, resistance W_{16} , high tension battery, earth. The impulses, therefore, which are prevented from operating the meter of the calling subscriber by the closing of contact $19z2$, are able to do so by the closing of contact $18z1$. Thus a premature release of the connection before all the metering impulses have been transmitted is prevented in that the contact $48x$, which is closed during the impulse transmission, sets up the following circuit for relay P: earth, contact $48x$, upper speaking lead, wiper a of the first group selector, contacts $16p$, $29c$, winding III of relay P, battery, earth. The release of the connection is only initiated by the release of relay P when contact $48x$ is opened after the last metering impulse.

According to the embodiment described above two additional relays are used in the normal group selector for effecting the metering operation, namely, the second metering relay Z_2 and relay E. In Fig. 2 the first group selector is of such a kind that the use of special relays is unnecessary. The devices preceding and following the group selector are not shown since they correspond to those of Fig. 1. In the same way the testing lead of the first group selector corresponds to that of Fig. 1 and is therefore not shown.

When the subscriber's connection has been set up as far as the group selector, Fig. 2, relays A and B energize over their windings II in the same way as described above. By the opening of contact $20b$ relay C is energized and locks up by closing contact $22c$. When the first digit is dialed relay A is intermittently deenergized. Contact $38a$ is accordingly closed corresponding to the impulses received and the following circuit is set up for the vertical magnet H_1 of the first group selector: earth, contacts $38c$, $39a$, winding II of relay V, contacts $43d1$, rotary off normal contact $42w$ opened after the first rotary step of the group selector, vertical magnet H_1 , battery, earth. The vertical magnet thus raises the group selector to a particular level. On moving away from the rest position the off normal contact $35k$ is closed. In the circuit for the vertical magnet relay V is also energized over its winding II. Its winding I is short-circuited over contacts $43d1$ and $42w$ so

that it possesses a definite delayed release property and holds up its contacts during the interruption of the circuit at contact $39a$. At the end of the impulse train, after the prolonged opening of contact $39a$ relay V deenergizes and closes its contact $36v$. The rotary magnet D_1 is thereby operated and closes its contact $44d1$. At this contact the following circuit is established for winding I of relay V: earth, contact $44d1$, winding I of relay V, vertical magnet H_1 , battery, earth. The vertical magnet cannot energize in this circuit. Relay V opens its contact $36v$ and thus breaks the circuit for the rotary magnet. This by closing contact $43d1$ causes relay V to deenergize again. This reciprocal play between the rotary magnet and relay V continues until the group selector has found a subsequent free connecting device. Thereupon the testing relay, which is not shown, energizes and by opening its contact $37p$ brings the group selector to rest. The closing of contacts $16p$ and $17p$ causes the switching through of the speaking leads to the next connecting device.

By the transmission of further impulse trains the subscriber establishes the connection to the desired subscriber. If the call is a local one battery potential is connected over resistance W_{15} to the lower speaking lead on the termination of the call in the same way as in the arrangement according to Fig. 1, whereupon the metering relay Z_3 , which is connected over contact $33c$ to the lower speaking lead, is energized in the following circuit: earth, winding of relay Z_3 , contacts $33c$, $17p$, wiper b of the first group selector, contact $21q$ or control switch contact S_9 , resistance W_{15} , battery, earth. By the closing of contact $34z3$ and the disconnection of resistance W_{12} thereby produced, the increase in current strength over the testing lead of the preselector which is necessary for advancing the meter once, is brought about.

The release of the group selector is again initiated by a contact of the metering relay, namely contact $30z3$, which short circuits winding III of relay P.

If the subscriber sets up a more highly rated call metering impulse trains of striking potential are transmitted at definite intervals over the lower speaking lead during the existence of the call. The metering relay Z_3 in the first group selector which is now connected in series with the glow lamp G_1 is energized, in accordance with the metering impulses, in the following circuit: earth, winding of relay Z_3 , glow lamp G_1 , contact $17p$, wiper b of the first group selector, connecting line VL , contact $47zf$, resistance W_{16} , high tension battery, earth. By the corresponding closing and opening of contact $34z3$ the impulses are transmitted to the meter of the calling subscriber. The metering relay Z_3 also operates contact $41z3$ in synchronism, whereupon the following circuit is set up for relay V: earth, contact $41z3$, windings II and I of relay V, vertical magnet H_1 (which cannot energize in this circuit), battery, earth. Relay V closes its contact $46v$ and thereby completes the short circuit for its winding II which was prepared by contact $45p$. Relay V is thus made slow to release, this feature being adjusted so that it holds up its contacts during the brief interruptions at contact $41z3$. Relay V thus opens contacts $31v$ and $32v$ during each transmission of a metering impulse train and thereby disconnects the speaking leads leading to the calling subscriber in order

to protect the subscriber from objectionable crackling noises produced by the impulses. A signal which indicates to the subscriber the occurrence of the metering is not represented in Fig. 2 but can, of course, be provided in the same way as in the arrangement according to Fig. 1. If the subscriber replaces his receiver during the transmission of an impulse train, the glow lamp is short-circuited by the release of relay C and the closing of contact 33c. The impulses which at this moment still remain to be transmitted, pass, over contact 33c, to relay Z3, so that the transmission of the metering impulse train is not disturbed by the clearing signal for the calling subscriber.

What is claimed is:

1. In a measured service telephone system, a calling subscriber's line, means including a group selector for setting up a connection from said line to a called line, a metering relay and a glow lamp connected in series to a talking conductor at the said group selector, said glow lamp normally maintaining said relay open, means beyond the group selector for transmitting high voltage impulses back to the group selector through a talking wiper thereof to break down said glow lamp and operate said metering relay, and a meter for the calling line controlled by said metering relay.
2. In a measured service telephone system, a calling subscriber's line, means including automatic switches for setting up a local connection or a toll connection from said line, a meter for the calling line, local and toll meter control circuits including a talking conductor, means effective over said local meter control circuit in the case of a local connection for operating said meter responsive to the release of the connection, means effective over said toll meter control circuit in the case of a toll connection for operating said meter before the connection is released, and means for preventing unbalance of the talking circuit during either a local or a toll connection, said last means including a glow lamp connected in said toll meter circuit to said line conductor for maintaining said toll meter control circuit open during conversation and including means for maintaining said local meter control circuit open during conversation.
3. In a measured service telephone system, a calling subscriber's line, means including an automatic switch for setting up a local or toll connection from said line, local and toll meter control circuits each including a talking wiper of said switch, a meter for the calling line controlled over said circuits, means including relay contacts for maintaining the local meter control circuit open during conversation, and a glow lamp for maintaining the toll meter control circuit open during conversation.
4. In a measured service telephone system, means including automatic switches for setting up connections from a calling line to called lines, a meter for the calling line, a meter control relay, a glow lamp, means for operating said relay in series with said glow lamp to charge for one connection, and means for operating said

relay over a circuit excluding said lamp to charge for another connection.

5. In a measured service telephone system, means including automatic switches for setting up connections from a calling line to called lines, a meter control circuit including one talking conductor and a glow lamp, another meter control circuit including said talking conductor but excluding said lamp, and a meter for the calling line controlled over one circuit to charge for one connection and over the other circuit to charge for another connection, said glow lamp non-conductive during said other connection and conductive only in said one connection for rendering said first meter control circuit effective.

6. In a measured service telephone system, a calling subscriber's line, means including automatic switches for setting up a connection to a called line, a meter for the calling line, a metering relay adapted to control said meter while the connection is established, and a second metering relay adapted to take over and complete the control of the meter if the calling subscriber hangs up while the said first metering relay is operating.

7. In a measured service telephone system, means including an automatic switch for setting up connections from a calling line to called lines, a meter for the calling line, a meter control circuit including a talking conductor of an established connection, means for transmitting a series of metering impulses over said circuit to operate said meter, and a second meter control circuit substituted for the first upon release and effective to receive the remaining impulses of a series and to control said meter in accordance therewith in case the release is initiated while such series is being transmitted.

8. In a measured service telephone system, means including an automatic switch for setting up connections from a calling line to called lines, means for transmitting high or low voltage metering impulses back through a talking conductor of said switch depending upon the type of connection set up, a meter control relay permanently connected to said talking conductor in series with a glow lamp for receiving high voltage impulses, a meter control relay temporarily connected to said talking conductor upon the release of a connection to receive a low voltage impulse, and a meter for the calling line controlled by one or the other of said relays, said glow lamp only rendered conductive in response to high voltage metering impulses for controlling said first meter control relay.

9. In a measured service telephone system, a calling subscriber's line, means including a group selector and a final selector for extending a connection from said line to another line, means controlled over one talking conductor extending between said selectors for temporarily holding the connection after the calling subscriber has hung up, a metering relay in the group selector controlled over the other talking conductor from the final selector, and a meter for the calling line operated by said relay.

KURT WOLLACK.
